SIGNAL DEVICE

Filed Dec. 18, 1939

UNITED STATES PATENT OFFICE

2,240,378

SIGNAL DEVICE

Lloyd Rittenhouse, Honeoye Falls, N. Y., assignor
to The A. E. Rittenhouse Co., Inc., Honeoye
Falls, N. Y., a corporation of New York

Application December 18, 1939, Serial No. 309,863

3 Claims.

(Cl. 177—7)

This invention relates to a signal device, and has to do particularly with the type of construction including a chime element, a resonance chamber, and electrically operated striker mechanism embodying a solenoid, the plunger of which is provided with a striker for engagement with the chime element.

A principal object of the invention is to afford a structure of simple design, which can be manufactured at a low cost, by reducing the number of operations and eliminating the use of brackets, screws, or similar attaching means for holding the solenoid in place.

Another purpose of the invention is to afford a construction in which the solenoid is readily accessible, making it easy to replace if necessary, while at the same time concealing it from view so as to afford a pleasing appearance and permit the use of variously designed housings, which is of importance where the device is intended for residential use.

An additional object is to afford an arrangement of such a character that the solenoid is held rigidly in its proper relation to the chime element and to the resonance chamber, so that there is no possibility of the solenoid plunger shifting from its correct alignment.

A further purpose is to afford a construction that permits of positioning a solenoid in close proximity to the chime element so that the plunger does not require an extension to engage the chime element.

Another purpose of the invention is to afford a structure that lends itself to the production of a stiff, rigid, and strong housing, and which retains the solenoid more securely and protects it more effectively than in prior constructions.

To these and other ends, the invention consists in the construction and arrangement of parts that will appear clearly from the following description when read in conjunction with the accompanying drawing, the novel features being pointed out in the claims following the specification.

In the drawing:

Fig. 1 is a rear elevation of a signal device constructed in accordance with a preferred embodiment of the invention;

Fig. 2 is a vertical sectional view on the line 2—2 of Fig. 1, looking in the direction indicated;

Fig. 3 is a plan view with the chime bar removed, and

Fig. 4 is a horizontal sectional view on the line 4—4 of Fig. 1 looking in the direction indicated.

Referring more particularly to the drawing in

5 which like reference characters refer to the same parts throughout the several views, the structure includes a housing affording a resonance chamber and consisting generally of a back wall 1, which is adapted to be attached in any convenient manner to a supporting surface, and a front portion including side walls 2, top wall 3, bottom wall 4, and a front wall 5, which is curved as shown to merge into the top and bottom walls 3 and 4.

10 The back wall 1 is flanged at its edges, as indicated at 6, to fit closely within the front portion of the housing, and may be removably held in frictional engagement therewith by any suitable means such as interengaging recesses and projections on the flange 6 and the adjacent surfaces of the front portion of the housing, although the back wall may be permanently fixed in the housing if preferred.

15 8 designates a chime bar or other suitable chime element mounted suitably upon posts carried by the top wall 3, while the top wall 3 of the housing is provided with openings 9 which may be located on opposite sides of the vertical center of the housing under the chime bar 8, and permit vibration of the body of air within the resonance chamber 10 that is afforded in front of the back wall 1 by the enclosed housing.

20 11 designates a solenoid coil which is mounted on the rear face of the back wall 1, so as to be readily accessible from outside the housing in the event that it must be replaced. The back wall 1 also serves to enclose and protect the solenoid, and to maintain it securely in proper relation to the chime bar. This is accomplished by providing the back wall with a centrally arranged inwardly extending portion of dished or other formation, affording a U-shaped pocket 12

25 that extends downwardly from its upper end and is deepest at its upper portion, as indicated at 13, to receive the coil of the solenoid. The pocket has a shallower portion 14 therebeneath which gradually merges into the lower portion of the back wall as shown in Fig. 2. The portions 13 and 14 are separated by a shoulder 15 upon which the lower plate of the solenoid coil is supported, the coil being thus located between the shoulder 15 and the flange 6 located immediately over the solenoid coil at the top of the back wall. The pocket or inwardly extending portion of the back wall may be of some other shape than that shown, and the solenoid may be secured therein by means other than that specifically set forth herein.

30 45 The pocket or dished portion 12 can be formed

50 55

in the back plate 1 by a punch-press operation, and after the solenoid coil is positioned, it may be securely locked within the recess in the back plate by punching or striking inwardly the upset portions 16, see Fig. 4, which engage the coil and hold it securely in place. The solenoid includes a plunger 17 having a striker tip 18 that engages the chime bar 8 when actuated upwardly, and the top wall 3 of the housing is provided with a central opening 19 through which the plunger is projected to engage and strike the chime bar. In the arrangement shown, the top of the solenoid is located adjacent to the top wall 3, and when the plunger is actuated upwardly, it moves through the opening 19 to strike the chime bar, the vibrations of the latter being imparted to the column of air in the resonance chamber through the aforementioned openings 9 on either side of the center of the chime bar.

The resonance chamber lies between the front portion of the housing and the back wall 1, and is separated from the solenoid by the inwardly extending or dished portions 13 and 14, which enclose the solenoid and protect it against accidental damage or injury. The solenoid is entirely within the pocket provided by the dished portions 13 and 14, and its outermost portion is flush with the adjacent outermost portions of the back wall.

While the invention has been described with reference to the details of construction herein shown, it is not confined to this particular embodiment, and the application is intended to cover such changes or modifications as may

come within the purposes of the improvement and the scope of the following claims.

I claim:

1. A signal device comprising a housing affording a resonance chamber and including top and front walls and a back wall having a pocket extending inwardly of the resonance chamber, a solenoid coil secured in said pocket against the rear face of the back wall and accessible from the outside of the housing, a solenoid plunger, and a chime bar secured to the housing and located in the path of the solenoid plunger.

15 2. A signal device comprising a housing affording a resonance chamber and including a top wall and front and back walls, said back wall extending inwardly of the resonance chamber, at its top central portion to afford a pocket, a solenoid mounted in said pocket, a solenoid plunger, and a chime bar secured to the housing adjacent to the top wall, the top wall having an opening through which the solenoid plunger is movable to engage the chime bar.

20 3. A signal device comprising a housing affording a resonance chamber and including a top wall and front and back walls, said back wall having a portion extending inwardly of the resonance chamber, a solenoid secured in said inwardly extending portion to the rear face of said back wall and having a vertically operating plunger, and a horizontally arranged chime bar secured to the housing above the top wall, the top wall having an opening through which the solenoid plunger is movable to engage the chime bar.

LLOYD RITTENHOUSE.
